Specification of Letters Patent. Patented Apr. 17, 1917.

Application filed August 18, 1914. Serial No. 857,334.

To all whom it may concern:

Be it known that I, ROBERT D. HAYES, a citizen of the United States, residing in the city and county of New Haven, State of Connecticut, have invented certain new and useful Improvements in Indexes or Files, of which the following is a full, clear, and exact description.

This invention relates, in its primary aspect, to indexes, files, lists or directories of the general type disclosed in Letters Patent No. 1048058, granted to Irving Fisher on December 24, 1912. In devices of the kind in question there are provided a plurality of individually movable supporting members each of which serves as a carrier for a plurality of cards or other record members, disposed lengthwise of the corresponding support. Furthermore, the supports or carriers are so arranged as to provide for the overlap of the series of cards or record members carried by one support or carrier relative to the series of cards or members mounted on another support or carrier; and, by preference the cards on each carrier will overlap each other to expose the margins thereof, so that the index as a whole presents a plurality of rows of record members so arranged that the members of each row overlap each other in one direction and the members of the adjacent row in another direction. In the particular index shown in said patent the carriers or supports are individually movable and insertible at any desired point with respect to the index as an entirety, and they are freely slideable relative to each other, in a direction lengthwise of the main supporting frame. The overlap of one row of cards relative to the adjacent row is produced by fixing the bodies of the carriers or supports at an acute angle with respect to the main supporting frame, whereby each row of cards when in assembled position, is rigidly held at an acute angle to the plane of the main supporting frame.

One of the primary objects of the present invention is to furnish an index or file of the general type mentioned, or a somewhat similar type, in which the compactness of the device is increased to a large extent. In other words, it is intended to provide an index or file in which the card capacity, *i. e.*, the capacity for mounting the ordinary paper index cards or other record members, is very great as compared to the space occu-

pied by the index. It is also desired, of course, to effect this result without sacrificing visibility or ready individual interoperability and removability of the carriers or supports; and I have not only attained this end, but have provided a construction in which the individual carriers or supports can be inserted and removed with even more facility than heretofore.

The advantages of my index are largely the result of providing record supports or carriers which are not only slideable with respect to each other, so as to bring them more or less closely together, but are also hinged to swing relatively to each other, whereby the desired compactness can be obtained at the same time that facility of manipulation is increased. It will be understood, of course, that the particular method of mounting each carrier or support so that it will swing as well as slide relative to the other supports does not interfere in any way with the ready removal of a support at any desired point, and ready insertion of the same or another carrier or support at the same or another point without the necessity of readjusting individually each support on either side of such point. By hinging the carriers or supports they may be closely grouped together at a comparatively large angle to the general plane of the main supporting frame, so that the device is very short in length and takes up very little floor space. Each carrier or support has cards mounted on both faces of the same, instead of on one face only, as heretofore. This is a large factor in increasing the card capacity, and yet the visibility of the cards is not sacrificed, and, on the other hand, the manipulation of the index is facilitated, owing to the fact that the carriers or supports may be freely swung to such a position as to expose the desired row of cards.

Other objects of the invention are to provide means for slanting the edges of the cards along the edges of the carriers or supports in order to increase the visibility of the index; to provide an index in which the cards may be placed on the carriers by sliding them on from the bottom as well as by fitting them over the carrier at an intermediate point; to provide an improved form of sliding hinge, adapted for use in card indexes and for other purposes; to provide an improved form of movable stop for the car-

riers or supports; and to improve the general construction and operation of devices of the class to which the invention relates.

To these and other ends the invention consists in the novel features and combinations of parts to be hereinafter described and claimed.

In the accompanying drawings.

Figure 1 is a front elevation of an index or directory embodying my improvements, with the leaves or carriers swung open;

Fig. 2 is a top plan view of the device shown in Fig. 1;

Fig. 2^a is a diagrammatic plan view showing the slanting or beveling of the bodies of cards at the forward edges of the carriers or leaves;

Fig. 3 is a side elevation of Fig. 2;

Fig. 4 is an enlarged detail of one of the carriers or supports showing how it is mounted on the main supporting frame;

Fig. 5 is a fragmentary view of the carrier shown in Fig. 4, looking from the opposite side;

Fig. 5^a is a view of Fig. 5, with the cards omitted;

Fig. 6 is an enlarged section on line 6—6 of Fig. 4;

Fig. 7 is a detail perspective view of one of the movable stops;

Fig. 8 is a detail face view of one of the record cards or members;

Fig. 9 is an enlarged sectional elevation, partly broken away, of a carrier or support of somewhat modified form;

Fig. 10 is a section on line 10—10 of Fig. 9; and

Fig. 11 is a section on line 11—11 of Fig. 9.

In the drawings I have shown the improved device as comprising a foundation board 20, and a plurality of slidably hinged carriers, supports or leaves 21, adapted to mount a plurality of cards or other record members 22. At the top and bottom respectively of the foundation board 20, are guides 23, in respect to which the carriers or leaves 21 are slidably and hingedly mounted, as hereinafter described, so that the series of carriers or leaves may be swung open at any desired point, as shown. When thus swung open the leaves or carriers at one side of the index are adapted to be supported in inclined position by a movable inclined stop 24, associated with the foundation board, and a similar stop 24 is adapted to support the leaves or carriers at the other side of the device in a similar way. However, while I have shown the carriers and the movable stops mounted on a special foundation board, it will be understood that in some cases the foundation board may be omitted and that the carriers and the stops may be applied more or less directly to the wall of a room, for example, or to a supporting

column or other structure, relative to which the carriers or leaves may swing in a horizontal plane. On the other hand, the device may be so mounted that the carriers or leaves are arranged to swing in a vertical plane, in which case the foundation board 20 will usually be retained.

Referring now to the details of the construction, it will be noted that the guides 23 are formed of grooved strips applied to the front face of the foundation board, and facing in opposite directions. Each carrier is provided with means to engage both of these strips, *i. e.*, the upper as well as the lower strip, in such a manner as to slide and swing with respect thereto. In the particular form shown each carrier or leaf 21 consists of a flat plate, preferably of metal, suitably reinforced at the edges, and having spring arms 25 at the top and bottom, with projections 26 on said arms to engage the respective retaining strips or elements 23, as shown in Fig. 4. The spring arms 25 preferably extend inward to a certain extent beyond the inner edge of the corresponding leaf or carrier, and the enlargements 26 take the form of balls, which are adapted to be sprung into the grooved guide strips 23 to engage the same slidably and hingedly. By preference the spring arms 25 will be formed as extensions on metal rods which reinforce the margins of the leaves or carriers, but this is not essential. The spring in the arms permits the latter to be sprung apart so that the carrier or leaf may in effect straddle the guide strips 23, with the balls 26 in engagement with the guide grooves, whereby the carrier is detachably connected with its support. When the carrier is mounted on the support it may travel freely therein in a longitudinal direction by movement of the balls 26 lengthwise in the guide strips, and the engagement of the balls in the guide strips also permits the leaf or carrier to be swung on opposite sides of a plane perpendicular to the foundation board, as shown in Fig. 2. The movable stops 24 prevent the leaves or carriers from being swung to such an acute angle relative to the plane of the foundation board as to cause the balls 26 or members 22 to be pried out of the socket members 23. Moreover, the movable stops 24 hold the leaves in an inclined position, as shown in Fig. 2, so that the cards may be easily read, and furthermore, they are adapted to hold the carriers in a more or less closely grouped relation as may be desired, and to prevent the carriers from being accidentally moved off the ends of the guide strips.

Each stop 24 may consist of an inclined portion 27, adapted to engage the carriers at the proper angle, and a supporting part 28, adjustably secured to the foundation board. In the embodiment illustrated the support 130

ing part 28 of the stop consists of toggle members 29, pivoted together at 30, fixed to the stop portion at 31, and having terminal members 32 to engage the guide strips. When the toggle members 29 are sprung inwardly, as shown in Fig. 3, the terminal members 32 will be retained in tight engagement with the corresponding guides 23, as shown in Fig. 3, so that the stop is securely fixed in position in the desired longitudinal adjustment relative to the guides. When the toggle members 29 are sprung outward, as shown by the full lines in Fig. 7, the terminal members 32 will disengage the guide strips 23 so that the stop may be removed. The stop portion 27 is preferably made of a light metal rod, which is sufficiently yielding to permit the angular movement of the toggle members relative to each other; and in fact, the toggle members may be clamped in position and released by pushing or pulling, respectively, on the stop portion 27. The portion 27 serves as a stop to directly engage the body portion of the adjacent carrier, or the cards on said body portion, and suitable projections 33 at the upper and lower extremities of the stop are adapted to engage the balls 26 and thereby prevent them from being moved lengthwise out of the retaining strips when the body portion of the carrier adjacent the stop member is not in a position to engage the stop portion 27.

The carriers or leaves 21 preferably consist of sheet metal plates, each having on both side faces thereof, guide devices for the cards or other record members. Preferably the record members will be in the form of cards having integral tongues 35, as described in Fisher Patent No. 1048058, and the guide devices 34 will preferably comprise elongated strips adapted to be engaged by the tongues 35 at opposite side edges, substantially as shown in said patent. The edge portions 34* of each guide strip 34 are of course spaced outward from the face of the leaf 21 to such an extent as to permit the tongues 35 to pass behind said edge portions 34*. In the form shown the guide strips 34, at opposite faces of the leaf, are both attached to the leaf by the same securing means, to wit, by means of a plurality of eyelets 36 passing through both strips and through the leaf or carrier interposed therebetween, as shown in Fig. 6. The eyelets 36 are spaced apart at suitable distances throughout the length of the guide strips and are passed through portions of said strips which are in contact with the leaf, the marginal portions of each strip being offset and spaced from the leaf to form the guide portions 34*, as described. Suitable retaining clips or hooks 37 are preferably associated with the lower end of each guide strip 34, to support from beneath the row

or series of cards guided on said strip, and in the form shown there are two clips on each side face of the leaf or carrier disposed on opposite sides respectively of the card on the supporting strip. The cards 22 may be flexed laterally in order to engage the tongues 35 back of the offset edge portions of the guide strip, or a series of cards may be slid onto each guide strip from the bottom, over the clips or hooks 37, after which the cards are moved down into the clips which then support them, in the manner shown particularly in Figs. 4 and 5. The manner of mounting the cards and of interpolating new cards is substantially the same as in the Fisher patent above mentioned.

In order to increase the visibility of the index, when the carriers or leaves are closely grouped together, I provide means for producing a slant or bevel of a row of cards along the front or outer edge of the corresponding leaf or carrier, whereby inspection of the forward edges of the cards on the next adjacent carrier is facilitated. In other words, by slanting the cards in this way the user of the index is enabled to see farther into the space between two adjacent leaves than he would be otherwise. This slanting of the cards is produced, in the form shown, by supporting the lower edge of the lowermost card on each leaf on a line out of perpendicular to the longitudinal axis of the leaf or carrier, as shown, for example, in Figs. 4 and 5. It will be noted from Fig. 4 that the front clip or hook 37 is at a somewhat higher elevation than the rear clip or hook 37, so that the lower edge of the lowermost card is slanted downwardly and rearwardly to a certain extent. This results in the other cards taking the same slant with respect to the upright guide strip with which they are engaged, and thereby the edges of the cards,—or more properly speaking—the edge of the body of the cards, is beveled or slanted at the outer edge of the leaf or carrier, as shown. Referring to Fig. 5, it will be noted that on the opposite face of the same leaf the slant of the cards is in the opposite direction, the front clip or hook 37 being located somewhat below the rear clip or hook 37. In this manner the forward edges of the two bodies of cards on opposite faces of the carrier or leaf are both slanted or beveled in the same direction. Thus the leaf and the bodies of cards on opposite sides of it present as a whole a beveled edge 38, which may be very useful, for example, in increasing the visibility of the cards when the leaves are swung over to the left with reference to Fig. 2. In other words, when the leaves are in the position shown at the left of Fig. 2 and in Fig. 2' the beveling of the bodies of cards enables one to inspect the margins of the cards on the right hand faces of the leaves or carriers to a greater extent.

than would be possible if the edges of the cards were not slanted or beveled.

Figs. 9, 10 and 11 show a slight modification of the construction, in which the ball 5 members for guiding each carrier or leaf on the main support are separately formed, as shown at 26^a and 26^b. The upper ball 26^a is rotatable freely on a portion 25^b of the carrier which is formed by bending downward and inward a portion of the spring arm 25^a.

The guide strip 23^a is turned up slightly so the ball 26^a will overhang the same to a certain extent. The ball 26^b is freely rotatable on an extension 25^a on the spring arm 25^a, and engages a guide strip 23^b of the special form shown. The guide strip or rail 23^b is provided with an inclined surface 23^c over which the ball 26^b rides as the carrier 20 is thrust toward the support so that the spring arms may be separated by the mere act of pushing the carrier laterally onto the guide or track, and without the necessity of grasping the arms and pulling them apart.

Figs. 9, 10 and 11 also show a modified, and perhaps a preferable, form of stop for the hinged carriers, to prevent them from swinging out of engagement with the guide strips. In this case the foundation board or 30 other support carries a fixed stop, which is adapted to engage the inner edge portions of a plurality of carriers. Preferably this fixed stop comprises an extension 40 on the upper guide strip, adapted to engage the 35 inner edge of each carrier when the latter is swung laterally, to a certain extent, in either direction, so as to arrest the carrier and prevent it from being swung loose from the guide strips. A similar extension 41 may 40 be provided on the lower guide strip to act as a stop in a similar manner. These stops project outward from the foundation board or other main support toward the carriers or leaves to an extent which will permit the 45 desired range of swinging movement of each leaf or carrier as will be obvious. Suitable projections or like members may be fixed at the ends of the guide strips, in this case, to prevent the carriers from sliding off the 50 guide strips at the ends, and of course various other changes may be made in the details as called for by circumstances. It will be observed that the guide strips form in conjunction a track, which is straddled by a 55 plurality of devices each carrying a plurality of cards or other record members.

The method of use of the improved device will be obvious, for the most part, from the foregoing description. In the particular 60 form shown the hinged carriers for the cards or other record members will all be swung to the left when the index is about to be used, so as to take up a minimum amount of space. The outer margins of the 65 cards or other record members on the right-

hand faces of the carriers are then visible to a certain extent, as shown more particularly in Fig. 2^a, and hence the particular card or cards to which access is desired may be easily selected by running the eye down the margins of the hinged carriers. The visibility of the index in this respect is increased to a certain extent by beveling the edges of the bodies of cards, as previously described. When the desired location has 70 been found certain of the carriers are swung on their pivots to open up a space, as shown in Fig. 2, which permits ready access to one or more rows of cards for reading the contents of the same, or for inserting additional 80 cards at any desired point.

It is apparent that the index has a very large card capacity as compared to the amount of space which it takes up. The individual carriers or leaves 21 are not only 85 hinged in addition to being slidable, but they may be placed in and removed from position on the main support with very little effort. When once placed in position, moreover, dislocation is effectively prevented, except when it is desired to remove a carrier, which can be easily done by springing apart the spring arms 25 thereof, so as to disengage the guide strips. The arms may be sprung apart merely by pulling the carrier 90 toward the operator. By the sliding arrangement of the carriers an additional carrier may be inserted at any desired point, and by hinging the carriers manipulation of the index is made very easy, for access to 95 either face of a carrier is readily provided. Furthermore, the slidable hinging of the carriers enables them to be closely grouped together at a comparatively large angle to the plane of the main support, so that the index 100 is rendered comparatively short and takes up very little floor space.

The above description enters into the details of the particular forms of my invention which have been selected for illustration and description, but it will be understood that the invention is not limited to such details, and that various modifications of the construction may be adopted within the scope of my inventive idea as expressed 115 in the claims.

What I claim is:

1. In an index or file, a guide, a carrier, and means for slidably hinging the carrier to the guide such that it may be removed from the guide at an intermediate point; substantially as described.
2. In an index or file, the combination of a track or guide, a plurality of record carriers, and means for slidably hinging said record carriers to said track or guide such that each carrier is attachable and removable independently of the others; substantially as described.
3. In an index or file, the combination of 130

- a guide, a plurality of carriers, and means for slidably hinging said carriers to said guide such that each is attachable and removable independently of the others at any point in the guide; substantially as described. 70
4. In an index or file, the combination of a guide, a plurality of carriers, means for slidably hinging each carrier to said guide such that it is freely attachable and removable at any intermediate point in the guide independently of the other carriers, and a plurality of record members mounted on each carrier; substantially as described. 75
- 10 5. In an index or file, the combination of a main supporting means, and a plurality of slidably hinged leaves or carriers each freely removable from said supporting means without disturbing the others; substantially as described. 80
- 15 6. In an index or file, the combination of a main support, and a plurality of hinged leaves or carriers slidable lengthwise of said support and each freely attachable and removable without disturbing the others; substantially as described. 85
- 20 7. In an index or file, the combination of a track or guide, a plurality of record carriers, and means for slidably hinging said record carriers to said track or guide in such a manner that an intermediate carrier is freely attachable and removable with respect to the track or guide without shifting the other carriers. 90
- 25 8. In an index or file, a plurality of card carriers, a common support therefor, and means for slidably hinging each carrier on said support in a detachable manner; substantially as described. 95
- 30 9. In an index or file, the combination of a track and a plurality of hinged record members slidable lengthwise of said track and each individually attachable and removable in a lateral direction relative to said track; substantially as described. 100
- 35 10. In an index or file, the combination of a guide, a plurality of carriers disposed transversely of the guide, means for slidably hinging each carrier to the guide, and a row of record members extending lengthwise of each carrier and transversely of the guide; substantially as described. 105
- 40 11. In an index or file, the combination of a two-rail track or guide, a plurality of record carriers, and means mounted on said record carriers for slidably hinging the latter to said track or guide such that an intermediate carrier is freely attachable and removable with respect to the track or guide without shifting or disturbing the other carriers, and such that each carrier is attachable and removable at any point in the track or guide. 110
- 45 12. In an index or file, the combination of a horizontally disposed track comprising spaced strips or rails, a plurality of vertically disposed carriers, means for slidably hinging each carrier to the respective strips or rails, and a vertically disposed row of record members mounted on each carrier; substantially as described. 115
- 50 13. The combination of a track or guide member having parallel retaining elements, a member adapted to slide on said track or guide member, one of said members straddling the other member, and said second named member being attachable to or removable from said track or guide member at any point in the length of the latter by lateral movement toward or away from said track or guide member; substantially as described. 120
- 55 14. The combination of a track or guide member having parallel retaining elements, and a member having spaced arms to engage said retaining elements, one of said members straddling the other, and said second named member being attachable to or removable from the first at any point in the length of said first member by a lateral movement toward or away from said first member, said second member adapted to swing relatively to said first member when the parts are assembled; substantially as described. 125
- 60 15. In an index or file, the combination of a track comprising spaced parallel members, a plurality of carriers, and means for slidably hinging each carrier to the respective track members; substantially as described. 130
- 65 16. In an index or file, the combination of a track comprising parallel spaced members, a carrier disposed transversely to said track, and means for slidably hinging said carrier to the respective track members such that said carrier is attachable and removable at any intermediate point; substantially as described. 135
- 70 17. In an index or file, the combination of a track, and a plurality of hinged carriers mounted on the track and each interpolable at any point in the length of the track; substantially as described. 140
- 75 18. In an index or file, the combination of a guide and carrier, one of said parts straddling the other, and permitting a relative swinging movement, and a plurality of record members mounted on the carrier; substantially as described. 145
- 80 19. In an index or file, the combination of a horizontal track, a carrier disposed transversely to the track, one of said parts straddling the other so as to permit a swinging movement of the carrier, and a plurality of record members mounted on the carrier; substantially as described. 150
- 85 20. The combination of a track or guide member having parallel retaining elements, a member having spaced arms to engage said

- retaining elements, one of said members straddling the other, and said second named member being attachable to or removable from the first at any point in the length of 5 said first member by a lateral movement toward or away from said first member, said second member adapted to swing relatively to said first member when the parts are assembled, and stop means for limiting the 10 swinging movement of said second member so as to prevent the disengagement of said arms from said retaining elements; substantially as described.
21. The combination of a track comprising 15 parallel elements, a member having arms engaging said track to slide or swing thereon, said member attachable to, or removable from said track at any point in the length of the latter, and being constructed so that said arms disengage said track when said member is swung to a predetermined extent, and stop means for limiting the swinging movement of said member relatively to said track, so as to prevent the 20 disengagement of said member from the track under normal conditions; substantially as described.
22. In an index or file, the combination of an upright support, a plurality of upright carriers having arms slidably hinged to said support, and a row of record members mounted on each carrier; substantially as described.
23. In an index or file, the combination 30 of a support, a carrier strip, a plurality of cards mounted on said strip, and means for securing said strip on said support as the same is pushed toward and against said support; substantially as described.
24. In an index or file, the combination 35 of a track or guide, an element adapted to mount a plurality of record members, and means for securing said element on said track or guide as said element is pushed laterally toward and against said track or guide, said element removable from said track or guide by pulling it laterally away from said track or guide; substantially as described.
25. The combination of a track, a member 40 attachable to and removable from said track at any point in the length of the latter, said member adapted to swing on the track and to disengage the same when swung to a predetermined extent, and means for limiting the swinging movement of said member; substantially as described.
26. In an index or file, the combination of 45 a support, retaining strips mounted thereon, and a carrier having spring arms slidably and hingedly engaged with said retaining strips; substantially as described.
27. In an index or file, the combination of 50 parallel retaining strips, and a carrier, having spring arms coöperating with said retaining strips; substantially as described.
28. In an index or file, the combination of 55 a support, grooved retaining strips mounted thereon, and a carrier having parallel spring arms slidably and hingedly engaged with said retaining strips; substantially as described.
29. In an index or file, a support including 60 parallel grooved members and a carrier having spring arms at opposite ends, and projections on said spring arms fitting said grooved members and slidably therein; substantially as described.
30. In an index or file, the combination of 65 a foundation board, parallel grooved strips carried thereby, and a plurality of carriers slidably hinged to said foundation board by means of spring arms on said carriers, engaging said strips; substantially as described.
31. In an index or file, the combination of 70 a track or guide having parallel retaining elements, a card supporting member, a plurality of cards supported on said member, and attaching arms on said card supporting member, at least one of said arms having a certain amount of resiliency, so that the terminal portions of the arms are adapted to be moved relatively to each other, said track or guide so constructed that said card supporting member may be attached thereto at any point in the length thereof by pushing said arms laterally toward and against said retaining elements, said member being removable from said track or guide by pulling said arms laterally away from said retaining elements; substantially as described.
32. The combination of a track or guide 75 having parallel grooved retaining elements, a member having attaching arms for engaging the respective retaining elements, said arms being engageable with said retaining elements by moving said member laterally toward said track or guide, at least one of said arms being resilient so that it may be sprung away from the other arm, and one of said retaining elements being constructed to spread said arms as they are moved against said retaining elements; substantially as described.
33. In an index or file, a row of record cards overlapping each other and slanted with respect to the line of the row to produce a shant or bevel at the side edge of the 80 row of cards; substantially as described.
34. In an index or file, the combination of a support, a plurality of cards slidable thereon and arranged to overlap each other, the body of cards being beveled or slanted at one side edge; substantially as described.
35. In an index or file, an elongated support, a plurality of cards thereon, and means securing said cards on said support, with

one side edge of the body of cards slanted or beveled; substantially as described.

36. In an index or file, a card carrier, a plurality of cards slideable thereon, and a bottom support for the cards slanted with respect to the longitudinal axis of the carrier; substantially as described.

37. In an index or file, the combination of a leaf or carrier, a plurality of cards slideable on said leaf, and means for supporting the lower edge of the lowermost card on a slant with respect to the longitudinal axis of the carrier; substantially as described.

38. In an index or file, a leaf or carrier, a strip secured on one face of the same, a plurality of cards having tongues to engage said strip, and clips on opposite sides of the strip for supporting the series of cards from beneath; substantially as described.

39. The combination of a track, a member slidably and detachably hinged to said track, and means for preventing detachment of said member from said track by a swinging movement of too much amplitude; substantially as described.

40. In an index or file, a leaf or carrier comprising a metal plate, rod portions reinforcing the margins thereof, and extended therefrom to form spring arms, and ball-shaped members at the free ends of said spring arms; substantially as described.

41. In an index or file, the combination of a support, a two-rail track on said support, a carrier element, a plurality of record members on said carrier element, and means to secure said carrier element to said track as it is pushed toward the same; substantially as described.

42. In an index or file, a leaf or carrier comprising a plate having a pair of spring arms for attaching it to a support; substantially as described.

43. In an index or file, the combination of a track comprising parallel members, arms to engage the respective members, a card supporting strip extending between and connecting said arms, and a plurality of cards slideable on said strip; substantially as described.

44. In an index or file, a card-carrying member having spaced supporting parts adapted to straddle a suitable track and to slide and swing on said track, said member laterally engageable with and laterally removable from said track at any point in the length thereof; substantially as described.

In witness whereof, I have hereunto set my hand on the 13th day of August, 1914.

ROBERT D. HAYES.
